Primary Examiner—Louis S. Zarfas*Assistant Examiner*—Frank Martinez*Attorney, Agent, or Firm*—Michael L. Hoelter; Salvatore J. Abbruzzese[57] **CLAIM**

The ornamental design for a wire marker printer keyboard, as shown and described.

DESCRIPTIONThe sole drawing **FIGURE** is a plan view of a keyboard, specifically arranged for use in a wire marker printer.

The broken line showing of the wire marker printer is for illustrative purposes only and forms no part of the claim designed.
